DESIGN.

—o—
A. L. FISHER.
BOTTLE CAP.

No. 19,861.

Patented May 27, 1890

UNITED STATES PATENT OFFICE.

ALVIN L. FISHER, OF NEW BRUNSWICK, NEW JERSEY.

DESIGN FOR A BOTTLE-CAP.

SPECIFICATION forming part of Design No. 19,861, dated May 27, 1890.

Application filed May 1, 1890. Serial No. 350,201. Term of patent 7 years.

To all whom it may concern:

Be it known that I, ALVIN L. FISHER, a citizen of the United States, residing at New Brunswick, in the county of Middlesex and State of New Jersey, have invented and produced a new and original Design for Bottle-Caps, of which the following is a specification, reference being had to the accompanying drawings, forming part thereof.

10 My design is illustrated in the accompanying drawings, in which—

Figure 1 represents a perspective view. Fig. 2 is a partial side elevation on a larger scale than the previous figure.

15 The leading features of my design are the scallops formed on the top edge of the bottle-cap, the spiral beads extending round the body of the cap, and the parallel bars which extend from the top edge of the cap across 20 the spiral beads to the bottom edge, one of the bars being made to terminate at the apex of each scallop, one at the lowest point of each scallop, and one in the middle of the sides of each scallop.

25 A is the body of the cap, and B is its top.

On the top edge are formed the scallops *a*, and the body is ornamented by spiral beads *b* and by vertical bars *c*, which are so placed that one bar extends from the apex of each scallop, one bar from the middle of each of 30 the sides of each scallop, and one bar from the lowest point of each scallop. (See Fig. 2.) The top *B* is ornamented by a central button *d* and by two concentric beads *e e*.

What I claim as new, and desire to secure 35 by Letters Patent, is—

The design for a bottle-cap herein shown and described, the same comprising the body *A*, the top *B*, the spiral beads *b*, the scallops *a*, and the parallel bars *c*, extending from the 40 scallops *a* across the spiral beads *b* to the bottom edge of the body, as set forth.

In testimony whereof I have hereunto set my hand in the presence of two subscribing witnesses.

ALVIN L. FISHER.

Witnesses:

J. VAN SANTVOORD,
E. F. KASTENHUBER.
